UNITED STATES PATENT OFFICE

2,065,329

WRINGER

Walter L. Kauffman, II, Erie, Pa., assignor to
Lovell Manufacturing Company, Erie, Pa., a
corporation of Pennsylvania

Application November 10, 1931, Serial No. 574,063

14 Claims. (Cl. 68—32)

Power wringers are usually provided with a safety release device which is intended to relieve the pressure on the rolls in case of accident. The present invention accomplishes such a release by detaching the top bar. The pressure of the tension means which must be released is quite large and where the release is accomplished against the frictional resistance of the engaged parts the effort for the operator is objectionable. The present invention is designed to obviate this by so effecting the release as to avoid such resistance. When the top bar, or parts are released, there is a tendency of the tension devices to throw the parts released which is objectionable. The present invention contemplates the arresting of this movement. The invention also contemplates an assembly and support of the bearings. Features and details of the invention will appear from the specification and claims.

A preferred embodiment of the invention is illustrated in the accompanying drawings as follows:

Fig. 1 is a front elevation, partly in section.
Fig. 2 an enlarged view of the latch end of the top bar and associated parts.
Fig. 3 a perspective view of the locking member of the latch.
Fig. 4 a section on the line 4—4 in Fig. 2.
Fig. 5 a perspective view of the releasing member of the latch.
Fig. 6 a perspective view of a stirrup construction forming the assembly and support for the bearing and a stop for the detached parts.
Fig. 7 a vertical section on the line 7—7 in Fig. 1.
Fig. 8 a section on the line 8—8 in Fig. 1.
Fig. 9 an elevation of a wringer frame partly in section showing a modification.

Fig. 10 a view of the latching end of a cross bar showing a further modification.

1 marks the base of the frame and 2 the side stiles. These are preferably formed of sheet metal. The side stiles are of box shape. 3—3 mark the wringer rolls, 4—4 the rods of the wringer rolls, 5 bearings for the lower roll, and 6 bearings for the upper roll, these bearings being mounted in the stiles from the top. The stiles are slotted on their inner faces at 7 permitting the entrance of the rods into the stiles and into place in the bearings. These slots preferably run through the top permitting the easy assembly of the rolls. A spring 8 is seated on the upper bearings. A top bar 9 is formed of inverted channel shape, the channels being

closed at the ends and the ends of the stiles extending upwardly into the channel opening. An adjusting screw 10 extends through a nut 11 which is fixed in the cross bar at its center. The screw is secured at 12 by a ball and socket joint with the spring. The stile at one end has a shoulder 13 struck up from its outer face and the end of the top bar has a corresponding lip 14 formed in it forming an engaging shoulder 15 below the cut forming the lip. This connection detachably connects the cross bar with the stile. At the opposite end of the cross bar a locking latch 16 is pivotally connected with the stile, the latch having perforations 17 which extend over ears 18 struck up from the front 15 and rear faces of the stile. The slot 17 is such as to permit a limited rocking movement of the latch and to form a stop limiting this movement so as to hold the latch member in position to be automatically engaged when the parts 20 are assembled. The locking latch member 16 extends to both sides of the stile having a connecting portion 19 extending around the outer face of the stile. The locking member has hooks 20. A releasing latch member 21 is of 25 channel form and extends over the top bar. It is provided with pintles 22 struck up from its sides and these pintles extend into openings 23 in the cross bar. Catch surfaces 24 are formed between the pintles 22 and the side 30 walls of the releasing member and these engage the hooks 20. A spring 25 is secured to the top bar and operates against the release member to yieldingly hold it in locked position. In the operation of the releasing mechanism, the operator depresses the release member and this rocks the engaging surfaces 24 without the necessity through the effort of the operator to overcome any frictional resistance. As soon as the surface 24 has been tilted sufficiently that 40 friction will not hold the hooks on the surface 24 the hooks slide off, the locking member swinging to permit this sliding movement and thus disengage the latch. The effort necessary to rock, or tilt, the surface is very slight so 45 that the disengagement may be readily accomplished. When this is disengaged the top bar swings up on the shoulders 15 and 13 until it has reached a high enough position to disengage the shoulder.

This upward movement of the top bar when released, is effected through the effort of the spring and unless the operator retains the grasp the parts are liable to be thrown. It is, therefore, desirable to retard this up-throw after the 55

release is accomplished. In the present invention the bearing blocks are provided with grooves 26 and a stirrup 28 and side plates 27 are arranged in these grooves. These side plates are 5 united by a top cross part 29, this being well above the spring in its normal position, but in the path of the spring as it moves up with the bar. The stirrup has indentures 30 which are 10 below the upper bearing and prevent the dropping down of the bearing into engagement with the lower bearing. Where this is in the hands of the operator, if this bearing does slide down to the lower position, the operator is confused as to the re-assembly of the parts. The lower end of 15 the side plates 27 are bent inwardly and form a base support 31 and this base support has the inner ends braced by plates 32, the ends of which rest on the struck-up shoulders 33 in the side stiles. Thus the lower bearing is supported, 20 the two bearings are arranged in the assembly and the stirrup at the top engages the spring as it moves upwardly so as to retard the upward movement of the top bar, the spring being secured at the center to the screw 18 and the 25 screw being secured in the top bar. While the bearings are assembled by simply placing them in at the top of the stiles, the weight of both rolls is sufficient to retard the upward movement of the top bar when the spring engages the 30 upper end of the stirrup. At the power end of the wringer the shaft 4 extends through a perforation in the outer wall of the side stile as indicated in Fig. 1 and inasmuch as this shaft cannot be lifted at this end this forms a positive 35 stop connection for the arresting stirrup 8 and the side stile. The spring striking the stirrup cushions the blow through a reverse deflection of the spring. In the structure shown in Fig. 1, the stirrups are arranged at both ends 40 so as to retard the upward movement of the cross bar under all conditions.

In Fig. 9 I have shown an alternative construction. In this structure the top bar 34 is provided with a fitting 35 in which is arranged 45 a release pin 36. The pin has an operating handle 37 and locking shoulders 38. The shoulders operate on cams 39 and are releasable through slots 40 extending through the fitting when they are turned at right angles. An adjusting screw 41 extends through the pin 36 and is secured to the spring. This releasing mechanism releases the pressure on the spring and operates substantially in the manner described in the reissue patent to Misner, #15,865. 50 The side stile has a shoulder 42 and a lip 43 is struck out of the top bar 34 forming a shoulder 44 which engages the shoulder 42 locking this end of the cross bar in the manner similar to that shown in Fig. 1. At the opposite end of 55 the cross bar a latch 45 is pivotally mounted on a rod 46. The latch has a hook 48 which engages a struck-up ear 49 on the stile. The latch has an extension 50 and these extensions are connected by a cross plate 50a, the latch extending to both sides of the cross bar through 60 the connecting extension which is arranged within the top bar. An ear 51 extends from the cross plate 50a and engages the under-side of the cross bar to locate the latch so that the 65 hooks will automatically engage the ears when the bar is put in position. When the release device is operated and the tension of the spring is released, the spring as released is thrown violently upwardly and the end engages the cross plate 50a and opens the latch. In order to per-

mit the use of a spring of greater initial curve I prefer to use in this structure the same stirrup 27 as is shown in Fig. 1 operating on the end of the spring opposite the latch so that that end of the spring is more definitely retarded and consequently the opposite end of the spring is more definitely lifted so as to effect a release of the latch. Ordinarily no stirrup is used in the latch end of the wringer shown in Fig. 9.

In Fig. 10 I have shown an alternative construction in which the disengagement of the latch for the top bar is accomplished without overcoming the resistance incident to the frictional engagement of the locking parts. In this structure a top bar 52 carries a latch 53 which is pivoted by a bolt 54 extending through the top bar. It is provided with a hook 55 engaging an ear 56 on the stile. It will be understood that the stile has the ears 56 at both sides and that the latch 53 extends through a connection 53a at the opposite side of the cross bar. A release lever 57 is pivoted on the bolt 54 and the end 58 of this lever extends through a perforation 59 in the wall of the side stile. The other parts of this structure are similar to those shown in Fig. 1. When the release lever is depressed, the engagement between the hook 55 and ear 56 is broken, the hook being moved slightly downwardly from the surface of the ear. The latch 56 through the cross member 53a is weighted by the cross member so that as soon as the frictional resistance of the surfaces is relieved the latch swings out permitting an immediate release of the hook surfaces.

What I claim as new is:—

1. In a wringer, the combination of a frame having side stiles; wringer rolls; pressure applying means for the rolls; a quick release for relieving pressure on the rolls comprising a latch mechanism having pivotally mounted latch members, said members having opposing engaging pressure sustaining surfaces extending crosswise of the line of thrust between the pivots of the pivotally mounted members, said members being disengageable by relative movement laterally of 45 the direction of thrust, one of the members being tiltable with nonfrictional relative movement of the members; and means moving the tiltable member to a disengaging inclination for releasing the latching mechanism and relieving the pressure on the rolls.

2. In a wringer, the combination of a frame having side stiles; a top bar; wringer rolls; pressure applying means for the rolls reacting against the top bar; a quick release for relieving pressure on the rolls comprising a latch connection between the top bar and a stile, said connection having pivotally mounted latch members, said members having opposing engaging pressure sustaining surfaces extending crosswise of the line 60 of thrust between the pivots of the pivotally mounted members, said members being disengageable by lateral relative movement of the surfaces, one of the members being tiltable with non-frictional relative movement of the engaging surfaces; means moving the tiltable member to move the surfaces to a disengaging inclination for releasing the latching mechanism and disengaging the top bar from the stile; and a movable connection between the top bar and 65 the opposite stile.

3. In a wringer, the combination of a frame having side stiles; a top bar; wringer rolls; pressure applying means for the rolls reacting against the top bar; a quick release for relieving pres- 70

sure on the rolls comprising a latch connection between the top bar and a stile, said connection having pivotally mounted latch members, said members having opposing engaging pressure sustaining surfaces extending crosswise of the line of thrust between the pivots of the pivotally mounted members, said members being disengageable by lateral relative movement of the surfaces, one of the members being tilttable with 5 non-frictional relative movement of the engaging surfaces; means moving the tilttable member to move the surfaces to a disengaging inclination for releasing the latching mechanism and disengaging the top bar from the stile; a movable 10 connection between the top bar and the opposite stile; and means retaining the latch members in position to automatically engage as the bar is put in position on the stile.

4. In a wringer, the combination of an open 20 top rigid frame comprising a base and hollow side stiles; wringer rolls; bearings for the wringer rolls in the stiles; a top bar and plate spring assembly exerting pressure on the bearings of the upper roll, said spring reacting on the top 25 bar; a quick release for one end of the top bar; and an arresting member for the assembly extending telescopically into a stile and being guided by the stile; means positively limiting the upward movement of the member relatively to 30 the stile and arresting the assembly when the top bar is released; and a connection between the end of the top bar and the stile opposite the release.

5. In a wringer, the combination of a frame 35 having hollow side stiles and a top bar; wringer rolls; bearings for the wringer rolls in the stiles; a plate spring exerting pressure on the bearings of the upper roll and secured to and reacting from the top bar; a quick release for one end of 40 the top bar; an arresting member limiting, through said spring, the upward movement of said end of the top bar upon release, the top bar being vertically movable relatively to the member and said member being in the path of and 45 engageable by the spring in its upward movement with the top bar; and a connection between the end of the top bar and the stile opposite the release.

6. In a wringer, the combination of a frame 50 having hollow side stiles and a top bar; wringer rolls; bearings for the wringer rolls in the stiles; a plate spring exerting pressure on the bearings of the upper roll and secured to and reacting from the top bar; a quick release for one end 55 of the top bar; an arresting member for each end of the top bar limiting, through said spring, the upward movement of each end of the top bar upon release, the top bar being vertically movable relatively to the arresting member and 60 said arresting member being in the path of and engageable by the spring in its upward movement with the top bar and through said spring arresting the movement of the top bar when released; and a movable connection between the 65 end of the top bar and the stile opposite the release.

7. In a wringer, the combination of a frame 70 having hollow side stiles and a top bar; wringer rolls; bearings for the wringer rolls in the stiles; a plate spring exerting pressure on the bearings of the upper roll reacting from the top bar; a quick release for one end of the top bar; an arresting member limiting, through said spring, the upward movement of said one end of the top 75 bar upon release, the top bar being vertically

movable relatively to the member and said member being in the path of and engageable by the spring in its upward movement with the top bar; means positively limiting the upward movement of the member relatively to the stile and arresting, through said spring, the top bar when released; and a movable connection between the end of the top bar and the stile opposite the release. 5

8. In a wringer, the combination of a frame 10 having hollow side stiles and a top bar; wringer rolls; bearings for the wringer rolls in the stiles; a plate spring exerting pressure on the bearings of the upper roll and secured to and reacting from the top bar; a quick release for one end 15 of the top bar; an arresting member limiting, through the spring, the upward movement of said end of the top bar upon release, the top bar being vertically movable relatively to the member and said member being in the path of and 20 engageable by the spring in its upward movement with the top bar and retarding, through the spring, the movement of the top bar when released, said arresting member extending telescopically into a stile and being guided by the 25 stile; and a movable connection between the end of the top bar and the stile opposite the release.

9. In a wringer, the combination of a frame 30 having side stiles; a top bar; upper and lower wringer rolls; upper and lower bearings for the 35 rolls arranged in the stiles; a plate spring exerting pressure on the upper bearings secured to and reacting on the top bar; a quick release effecting a release of the top bar and relieving pressure on the upper bearings; and a stop member extending past an upper bearing and secured to the lower bearing, said member having a shoulder in the path of the spring when the top bar is released. 40

10. In a wringer, the combination of a frame 45 having side stiles; a top bar; upper and lower wringer rolls; upper and lower bearings for the rolls arranged in the stiles; a plate spring exerting pressure on the upper bearings secured to and reacting on the top bar; a quick release 50 effecting a release of the top bar and relieving pressure on the upper bearings; and a stirrup having sides extending downwardly past the lower bearing and secured thereto, said stirrup having a cross member at the top above the spring 55 adapted to retard the spring when released.

11. In a wringer, the combination of a frame 60 having side stiles; a top bar; upper and lower wringer rolls; upper and lower bearings for the rolls arranged in the stiles; a plate spring exerting pressure on the upper bearings secured to and reacting on the top bar; a quick release 65 effecting a release of the top bar and relieving pressure on the upper bearings; and a stirrup having sides extending downwardly past the lower bearing and secured thereto, said stirrup having a cross member at the top above the spring 70 adapted to retard the spring when released and having at its lower end a seat for the lower bearing. 65

12. In a wringer, the combination of a frame 75 having side stiles; upper and lower wringer rolls; upper and lower bearings for the rolls arranged in the stiles; a top bar and plate spring assembly, the spring exerting pressure on the upper bearings and being secured to and reacting on the top bar; a quick release effecting a release of the top bar and relieving pressure on the upper bearings; and a stop member for the assembly 80 extending past an upper bearing, said member 75

having a shoulder limiting the downward movement of the upper bearing.

13. In a wringer, the combination of a frame having side stiles; a top bar; upper and lower wringer rolls; upper and lower bearings for the rolls arranged in the stiles; a plate spring exerting pressure on the upper bearings secured to and reacting on the top bar; a quick release effecting a release of the top bar and relieving pressure on the upper bearings; and a stop member extending past an upper bearing and secured to the lower bearing, said member having a shoulder in the path of the spring when the top bar is released and a shoulder limiting the downward movement of the upper bearing.

14. In a wringer, the combination of a frame having side stiles; a top bar; upper and lower wringer rolls; upper and lower bearings for the rolls arranged in the stiles; a plate spring exerting pressure on the upper bearings secured to and reacting on the top bar; a quick release effecting a release of the top bar and relieving pressure on the upper bearings; and a stirrup having sides extending past the upper bearing and secured to the lower bearing, the stirrup having a cross member above the spring and adapted to retard the spring on the release of the top bar, said assembly of bearings and stirrup being slidably mounted in the side stiles.
